UNITED STATES PATENT OFFICE.

MAX N. AARON, OF PHILADELPHIA, PENNSYLVANIA, ASSIGNOR TO FRIEDBERGER-AARON MANUFACTURING COMPANY, OF PHILADELPHIA, PENNSYLVANIA, A CORPORATION OF PENNSYLVANIA.

LACE EDGING.

1,203,561.

Specification of Letters Patent.

Patented Nov. 7, 1916.

Application filed June 9, 1915. Serial No. 33,013.

To all whom it may concern:

Be it known that I, MAX N. AARON, a citizen of the United States, residing at Philadelphia, county of Philadelphia, and State 5 of Pennsylvania, have invented a new and useful Improvement in Lace Edgings, of which the following is a full, clear, and exact description, reference being had to the accompanying drawings, which form a part 10 of this specification.

The object of my invention is to produce a lace edging adapted for use as a pocket edging and also as a binding and is intended more particularly for application to ladies' 15 underwear.

The so-called pocket edging usually comprises a closely knit or woven backing of uniform texture connecting opposite sewing-on edges, which are also connected by 20 pairs of transversely extending threads disconnected from the backing and through which a ribbon may be interlaced in the well-known manner. Examples of such pocket edgings, provided with an ornamental border of special design, are to be 25 found in the Goodman patent of July 2, 1912, No. 1,030,996, and the Goodman design patents of July 9, 1912, Nos. 42,740; 42,741; 42,742; 42,743; 42,744; 42,745 and 42,746.

The object of my invention is to provide a 30 lace edging which may be sewed along its edge to the garment in such manner as to perform the function of a pocket edging but in which the cross-threads or "pillar-bars" will lie more flat and resist tendency 35 to distortion and in which the joinder of opposite ends, where the edging is sewed around the neck of the garment, and the slippage of the ribbon therethrough in the 40 process of tying opposite ends together, will be facilitated; while at the same time adapting the edging for use as a binding.

The invention will be understood by reference to the accompanying drawings, which 45 show a preferred embodiment of the invention and in which—

Figure 1 is a plan view of a portion of edging before folding. Fig. 2 shows a portion of edging on a garment and Figs. 3 and 50 4 are cross sections through edging, showing, diagrammatically, different forms of use. Fig. 5 is an enlarged detail plan view

of a small section of the edging of Fig. 1. Fig. 6 is a section through the fabric of Fig. 5. 55

The particular design of fabric is unimportant except so far as the presence of certain structural features thereof impart a peculiar general appearance to the fabric. These features are: (1) a sewing-on edge *a* 60 which may comprise a double line of chain stitches united by short and fine transverse threads; (2) a series of pairs of transverse threads *b*, forming pillar bars spanning a ribbon-space through which a ribbon may be 65 interlaced in the well-known manner; (3) an ornamental strip *c* which, while extending longitudinally along an intermediate part of the fabric, forms, in use, an ornamental tip or border, as will be hereinafter 70 described; (4) a comparatively closely and uniformly knit or woven section or backing *d*; and (5) a sewing-on edge *e*, which may be similar to the edge *a*. The backing *d* should be united to the tip or border *e* in such manner that the backing will readily fold back upon the parts *c* and *b*, and the two sewing-on edges *a* and *e* be brought in register. When the edges *a* and *e* are sewed to the 75 edge of the garment *x*, as shown in Fig. 4, a 80 pocket is formed to receive loops of a ribbon *y*.

One way of "hinging" together sections *c* and *d* is to sew to, or include in, the edge of the tip or border *c* a line of stitches *f* provided with loops *g* through which extend loops *h* of the backing *d*. By causing all the loops *h* to enter and emerge from the under side of loops *g*, the backing readily and naturally folds over. The tip or border *c* 85 may be composed of a plurality of lines of chain stitches which are sewed to and underlie a plurality of rows of loops, one row of which may be integral with the transverse threads *b* whose opposite ends are bound by 90 the inner row of stitches of the sewing on edge *a*.

It will, of course, be understood that the specific construction, as I have described it, necessarily produces a specific design appearance, which is not, however, necessary to an embodiment of my invention. The ornamental tip or border, the backing, the sewing-on edges, the pillar-bars, and the 100

manner of connecting the parts, may all be varied and interconnected in a manner different from the edging herein shown and described, which is merely illustrative.

5 Instead of applying the edging in the manner shown in Fig. 3, it may be applied as a binding in the manner shown in Fig. 4. In this manner of use, it performs the function of an ordinary binding and also accommodates a ribbon, if desired.

The specific edging shown in the drawings is a knitted fabric, although it will be understood that edgings of similar character are sometimes woven on a certain type of loom. 15 My invention, therefore, is not restricted to a knitted fabric.

Having now fully described my invention, what I claim and desire to protect by Letters Patent is:

20 1. A lace edging for garments comprising a fabric composed of two longitudinal sections of substantially equal width, interconnected loops hinging the sections together,

one section being of a comparatively close texture and having a sewing-on edge and the other section containing transverse threads spanning a ribbon space and provided with a sewing on edge.

2. An edging for garments composed of a longitudinal section comprising longitudinally extending rows of stitches forming between them a ribbon space and transverse threads uniting said rows, and a second longitudinal section in hinged relation to the first longitudinal section and comprising a 35 knitted web adapted to be folded over against the first section and form between the two sections a ribbon retaining pocket.

In testimony of which invention, I have hereunto set my hand, at Philadelphia, on 40 this 8th day of June, 1915.

MAX N. AARON.
